UNITED STATES PATENT OFFICE.

CHARLES J. DAHLGREN, OF EAST ORANGE, NEW JERSEY.

BUTTON-FASTENER.

1,290,919.

Specification of Letters Patent. Patented Jan. 14, 1919.

Application filed March 9, 1918. Serial No. 221,470.

To all whom it may concern:

Be it known that I, CHARLES J. DAHLGREN, a citizen of the United States, and a resident of East Orange, in the county of Essex and State of New Jersey, have invented a new and Improved Button-Fastener, of which the following is a full, clear, and exact description.

The object of the invention is to provide a new and improved button fastener arranged to permit the wearer of a garment, hat or other wearing apparel, to quickly and securely fasten a button to the wearing apparel. Another object is to permit the use of the fastener on various types of buttons such as cloth buttons, apertured buttons, eye buttons and the like. Another object is to provide a fastener which is simple and durable in construction and cheap to manufacture.

With these and other objects in view the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is an enlarged sectional side elevation of the fastener applied for fastening an eye button to a garment;

Fig. 2 is an enlarged inverted plan view of the button fastener with the parts in position illustrating the first steps in applying the fastener;

Fig. 3 is a similar view of the same with the parts in position illustrating subsequent steps in applying the fastener;

Fig. 4 is a similar view of the fastener as applied;

Fig. 5 is a side elevation of the fastener as applied to an apertured button, the latter, its spacing washer and the garment material being shown in section;

Fig. 6 is a plan view of a modified form of the button fastener; and

Fig. 7 is a plan view of another modified form of the button fastener.

The button fastener in its general construction consists of a staple 10 and a head or a back plate 11, of which the staple 10 is adapted to engage with its bent portion 12 a button 13 to be fastened to the material 14 of a garment, hat, shoes or other wearing apparel. In case the button 13 is

provided with an eye 15 then the bent portion 12 of the staple 10 engages the said eye, as plainly shown in Fig. 1, and in case it is a cloth button the staple is engaged with the attaching portion at the back of such button, and in case the fastener is used on an apertured button 16, such as shown in Fig. 5, then the staple is engaged with opposite apertures 17, as illustrated in Fig. 5.

The head 11, as shown in Figs. 1, 2, 3, 4 and 5, is preferably made in the form of a plate of sheet metal or other sheet material and consists of a base member 20 provided with a central aperture 21 through which the side arms 22 of the staple 10 are passed after the side arms of the staple are pushed through the material 14, as indicated in Fig. 1. The head 11 is further provided with a retaining member 23 integrally connected at one side by a neck 24 with one side of the base member 20, said neck being preferably integral with base member 23, and a capping member 25 is similarly connected at one side by a neck 26 with the other side of the base member 20 so that the two members 23 and 25 are connected with the opposite sides of the central member 20. The side members 22 of the staple 10 are made sufficiently long that after they are pushed through the central aperture 21 and bent over in opposite directions and at a right angle to the side members 23 and 25 their terminals project beyond the peripheral edge of the base member 20, as plainly indicated in Fig. 2. The retaining member 23 is now bent over on the base member 20 and then the terminals of the side members 22 are bent over on the outer face of the retaining member 23, as plainly indicated in Fig. 3, and finally the capping member 25 is bent over to overlie the retaining member 23 and the terminals of the side arms 22 of the staple 10 (see Fig. 4). It will be noticed that by the arrangement described the side arms 22 of the staple 10 are firmly engaged with the retaining member 23 and the capping member 25 practically incloses the retaining member 23, the base member 20 and the portions of the staple engaging the retaining member 23.

The base member 20 of the head 11 is preferably provided with a central ridge 30 surrounding the central opening 21 and adapted to abut against the rear face of the material 14, as plainly indicated in Figs. 1 and 5. The base member 20 is further provided with a rim flange 31 adapted to

inclose the retaining member 23 and the 5
bent portions of the side arms 22 extending
around the edge of the said retaining
member 23 (see Figs. 1 and 3). The cap-
ping member 25 is provided with a rim
flange 32 adapted to inclose the rim flange
31 thus practically forming a firm, close
joint with the rim flange 31 of the base
member 20, as will be readily understood
10 by reference to Fig. 1. The rim flange 31
is provided with cut-out portions 33, 34 for
the passage of the necks 24 and 26 when
bending the retaining member 23 and the
capping member 25 over into closed posi-
15 tion, as previously explained. By the ar-
rangement described an exceedingly neat
appearance is given to the button fastener.

It will be noticed that portions of the side
members 22 of the staple 10 extend between
20 the base member 20 and the overlying retain-
ing member 23, and the terminals of the said
side arms 22 extend between the retaining
member 23 and the capping member 25 so
that the staple is not liable to be pulled out
25 of the head even in case the button 13 is
subjected to a very severe strain.

In practice, the head 11 is made of thin
sheet metal, and the base member 20, the
30 retaining member 23 and the capping mem-
ber 25 are preferably made in disk form,
and the necks 24 and 26 are made narrow so
as to permit of conveniently bending the
members 23 and 25 over, as above explained.
The capping member 25 is preferably
35 slightly dished, as indicated in Figs. 1
and 5.

In case the button fastener is used for an
apertured button, as shown in Fig. 5, then
use is preferably made of a tubular washer
40 interposed between the back of the but-
ton 16 and the face of the material 14 and
inclosing portions of the side arms 22 of
the staple extending from the button to the
material 14. By the use of this washer 40
45 the button 16 is properly spaced from the
face of the material 14 to accommodate the
part of the wearing apparel to be engaged
by the button 16.

The button fastener shown and described
50 is very simple and durable in construction
and can be readily applied for attaching a
button to the material of a garment, hat,
shoe, or other wearing apparel and without
the use of special tools, the bending of the
55 points being done with the fingers of the
user. In case it is desired to disconnect
the button it is only necessary for the user
to bend with the fingers the capping mem-
ber 25 back into the position shown in Fig.
60 3, then bending the terminals of the side
arms 22 of the staple 10 out of engagement
with the retaining member 23 to allow of
bending the latter outward into open posi-
65 tion, as shown in Fig. 2. The side members
22 of the staple are then bent toward each

other to allow of pulling the staple out of
the central opening 21 and out of the ma-
terial 14 on exerting a pull on the button 13,
thus disconnecting the latter from the ma-
terial. The button fastener can then be re-
70 used if it is desired to do so.

Instead of making the head 11 from a
single piece of material, such head may be
made in three separate parts, as shown in
Fig. 6, but the construction of the base mem-
ber 20, the staple retaining member 23 and
75 the capping member 25 is the same as above
described, and the staple is connected with
the said members in the manner described.

In the modified form shown in Fig. 7, the
head 11 is made of a single piece of sheet
material and the base member 20 thereof
instead of being provided with a central
aperture 21 for the passage of the side arms
22 of the staple is provided with notches
80 40, 41 disposed diametrically opposite each
other to provide passages for the side arms
22 of the staple, otherwise the construction
is the same as above described in reference
to Figs. 1, 2, 3, 4, and 5.

Having thus described my invention, I
claim as new and desire to secure by Letters
Patent:—

1. A fastener for fastening a button to
wearing apparel, comprising a staple and a
head, the staple being adapted to engage
the button and the said head, the latter having
a base member provided with means
for the passage of the side arms of the
staple, a staple retaining member overlying
the base member, and a capping member
overlying the said staple retaining member,
a rim flange projecting from said capping
member, and the side arms of the staple en-
gaging the said base member and having a
portion extending between the said base
member and the said retaining member, and
the terminals extending between the said
retaining member and the capping member,
the rim flange of the capping member in-
110 closing the edge of the base member.

2. A fastener for fastening a button to
wearing apparel, comprising a staple and a
head, the staple being adapted to engage the
button and the said head, the latter having
115 an apertured base member, a staple retain-
ing member overlying the said base mem-
ber, and a capping member having a rim
flange and overlying the said staple re-
taining member, the side arms of the staple
120 passing through the said base member and
having a portion extending between the said
base member and the said retaining mem-
ber, the terminals of the said side arms ex-
tending between the retaining member and
125 the capping member, the rim flange of said
capping member inclosing the edge of the
base member.

3. A fastener for fastening a button to
wearing apparel, comprising a staple and a
130

head, the staple being adapted to engage the button and the said head, the latter having an apertured base member, a staple retaining member integrally connected at one side 5 with one side of the said base member, and a capping member connected integrally at one side with the other side of the said base member, the said retaining member overlying the said base member and the said 10 capping member overlying the said retaining member, the side arms of the staple extending through the apertured base member, a portion of the side arms extending between the said base member and the said retaining member, and the terminals of the said side arms extending between the said retaining member and the said capping member.

4. A fastener for fastening a button to wearing apparel, comprising a staple and a 20 head, the staple being adapted to engage a button and the said head, the latter having an apertured base member, a staple retaining member integrally connected at one side with one side of the said base member, and a 25 capping member connected integrally at one side with the other side of the said base member, the said retaining member overlying the said base member and the said capping member overlying the said retaining member, the side arms of the staple extending through the apertured base member, a portion of the side arms extending between the said base member and the said retaining member, and the terminals of the 30 side arms extending between the said retaining member and the said capping member, the said base member having a raised central ridge and a rim flange engaging the edge of the said retaining member and the said 35 capping member having a rim flange inclosing the rim flange of the said base member.

5. A button fastener for fastening a but-

ton to wearing apparel, comprising a staple adapted to engage the button and adapted 45 to have its side arms pushed through the material of the wearing apparel, and a retaining means adapted to engage the under side of the apparel material and having a base member and integral side members, the 50 base member being apertured for the passage of the side arms of the staple, portions of the said side arms being bent over on the outer face of the base member, one of the said side members being a retaining 55 member bent over and overlying the said base member and portions of the side arms extending between the said base member and the said retaining member, the terminals of the said side arms being bent over the outer 60 face of the said retaining member and the other side member being a capping member and being bent over and overlying the said retaining member and the terminals of the 65 said side arms.

6. In combination, a button having apertures, a staple engaging the said apertures, a spacing washer surrounding the staple and interposed between the under side of the button and the face of the material to which 70 the button is to be attached, the ends of the washer abutting the button and material respectively, and a head having a base member adapted to engage the back of the material, a retaining member overlying the 75 said base member, and a capping member overlying the said retaining member, a portion of the side arms of the staple extending between the said base member and the said retaining member, and the terminals of the 80 said side arms extending between the said retaining member and the said capping member, the latter inclosing the said base and retaining members.

CHARLES J. DAHLGREN.
